U.S. Appl. No. 62/139,124, filed Mar. 27, 2015, entitled "Canvas Mounting Device".

Primary Examiner — Mark Goodwin

(74) Attorney, Agent, or Firm — Irina Hass

(57) **CLAIM**

The ornamental design for a mounting device, as shown and described.

DESCRIPTION

FIG. 1 is a perspective view showing a new design for a mounting device;

FIG. 2 is a front view thereof;

FIG. 3 is a right side view thereof, a left side view being a mirror image thereof;

FIG. 4 is a rear view thereof;

FIG. 5 is a top view thereof; and,

FIG. 6 is a bottom view thereof.

The portions of the mounting device in FIGS. 3-6 shown in broken lines are included to show features that form no part of the claimed design.

1 Claim, 2 Drawing Sheets
